(57) **CLAIM**

The ornamental design for a drawer pull, as shown and described.

DESCRIPTION

FIG. 1 is a perspective view of a drawer pull showing my new design.

FIG. 2 is another perspective view thereof.

FIG. 3 is a front elevational view thereof.

FIG. 4 is a cross-sectional view taken along line 4—4 of FIG. 3, depicting the recessed portions of the front thereof.

FIG. 5 is a rear elevational view thereof.

FIG. 6 is a top plan view thereof; and,

FIG. 7 is a bottom plan view thereof.

The broken lines in FIG. 2 depict environment and form no part of the claimed design.

1 Claim, 3 Drawing Sheets**FIG. 1**

FIG. 2

FIG. 3

FIG. 4

FIG. 5

FIG. 6

FIG. 7
